HERMAN C. MUELLER, OF MILWAUKEE, WISCONSIN

AMPLIFYING CIRCUITS

Application filed December 31, 1928. Serial No. 329,397.

This invention relates to improvements in amplifying circuits such as are used in the reception of radio broadcast.

It is the object of the invention to provide a new and improved form of coupling between the successive inductances of such a circuit whereby relatively sharp tuning may be effected with a relatively high energy transfer. By sharpness, I will be understood to refer to the condition which obtains when an inductance is resonant to a comparatively very narrow band of frequencies at any given time. Obviously this condition is desirable in a radio signal receiver, since it enables the operator to receive a selected signal and to eliminate signals of closely adjacent frequencies. High selectivity, however, has heretofore been obtained only at the expense of volume and for this reason I have emphasized the fact that this invention is intended to give good volume while maintaining a desirable high selectivity.

In the drawings:

Figure 1 is a complete circuit diagram of an operative radio receiver of the reflex type embodying this invention.

Figure 2 is a slight modification of the invention as it appears in an antenna coupler suitable for use in the circuit of Figure 1, or in any other radio frequency circuit.

Figure 3 is a further modified antenna coupling device embodying the invention.

Figure 4 shows the application of the invention to an untuned radio frequency transformer.

Figure 5 is a detail view showing the mechanical structure involved in coupling two inductances in accordance with this invention.

Like parts are identified by the same reference characters throughout the several views.

While I have chosen to illustrate the application of my invention to a reflex circuit, it will be understood that the invention is equally applicable to other circuits. A re-

flex circuit, however, is generally considered as being more difficult of proper assembly than an ordinary radio frequency amplifier and consequently I have chosen this more difficult application of the invention by way of illustration. Conventional symbols are used throughout to show the several electrical devices which enter into my improved circuit.

The antenna at 10 is coupled through a small fixed condenser to a compound inductance made up of a variometer 12 and a solenoid, or other equivalent coil, 13. The other end of coil 13 is connected to a binding post at G which is intended to be grounded and will hereinafter be referred to as ground. The compound inductance made up of variometer 12 and winding 13 is shunted by a variable condenser 14 capable of tuning it as desired.

The first amplifying tube or triode 15 of the receiver is adapted to handle both radio frequency currents and also currents at audio-frequencies. Grid 16 is connected to a grid coil inductance 17 shunted by a tuning variable condenser 18. The grid return passes through the secondary winding 19 of transformer 20 to ground, such winding being by-passed by a fixed condenser 21. A filament 22 of each of the triodes 15, 25, and 26 is grounded on the negative side and is connected between terminals A- and A+, the lead to the A- terminal being controlled by the usual rheostat 27. A smaller variable condenser 28 is connected between the grid return lead from grid coil 17 to the plate 30 of triode 15 and serves to control feed-back through said tube.

The output of plate 30 passes through the usual radio frequency transformer including an untuned primary at 31 and a secondary 32 or grid coil at 33 tuned by variable condenser 33. In place of this transformer, the special design shown in Figure 4 and hereinafter to be described, may be substituted if desired. The primary 31 of the radio frequency trans-

former is supplied with current through the primary 34 of audio-frequency transformer having secondary 35 connected to the grid of triode 26.

5 The grid coil 32 is connected to the grid through a grid leak and by-pass condenser as diagrammatically illustrated. The filament return may be made either to the positive or negative filament leads according to 10 the type of triode employed as a detector. The plate output of this triode is led back through the primary winding 36 of transformer 20 to a binding post adapted to receive current at proper voltage.

15 The plate output of triode 26 leads to jack 37 having another lead to a positive binding post for high potential current. Any sort of reproducer may be coupled to the receiver at the jack 37.

20 It will be seen from the foregoing description that the circuit illustrated in Figure 1 is of standard construction with the exception of the coupling between the tuned antenna circuit and the tuned grid coil 17, 25 such coupling remaining to be described. The antenna coils 12 and 13 and the grid coil 17 are in non-inductive relation and are coupled solely by capacity.

The various views show a number of expedients for effecting the desired capacity coupling in accordance with this invention. The particular device employed in the Figure 1 illustration consists of the capacity which exists between adjacent strands of 35 wire and metallic strips or conductors. The metallic conductor 50 is positioned upon or within a portion of coil 13 and is insulated therefrom by means of some suitable interposed insulating means. Metallic conductor 40 51 is similarly positioned upon and insulated from a portion of grid coil 17. As a result of this arrangement, it will be noted that the antenna circuit is coupled to the grid circuit through two capacities and an intervening 45 conductor 52. While the capacitances 50 and 51 are illustrated in the form of metallic strips, it is not necessary that they be so arranged with reference to the antenna and grid circuits, since the coupling obviously 50 does not depend in any way upon a specific shape of the strips. It is particularly to be noted that a preferred embodiment of this invention includes a capacity which extends across several turns of coils in each of the 55 two circuits to be coupled. Thus the capacitance 50 is in capacitative relation to several turns of coil 13 and the capacitance 51 is in like relation to several turns of grid coil 17.

In the Figure 2 diagram, merely a fragment 60 of a receiver circuit is illustrated. Antenna 10 is coupled to ground through a tuned coil 45 controlled by variable condenser 14'. A switch at 46 allows the antenna to be connected, either directly to the coil or 65 capacitatively thereto, through the small

fixed condenser 47. The grid coil 17 and its tuning condenser 18 are arranged as described with reference to Figure 1. I have shown the connection of grid coil 18 to be effected by means of metallic conductors 50 70 and 51 and the intervening lead 52. If desired, a special connection may be made between the antenna and this series of conductors by means of the condenser 53. This adds slightly to the volume, but decreases 75 selectivity.

It will be noted that as in the former case, coupling is effected through two capacitances and an interposed conductor. It is true, also, 80 that the strips of metal shown at 50 and 51 are in capacitative relation to a large proportion of the turns of the two coils to be coupled. Selectivity may be controlled by the width of the strip of metal so employed. It is preferred that the strip should be approximately the length of the coil. A strip of this character if narrow, will give high 85 selectivity, whereas if the strip is wider, the tuning will be broadened and the volume correspondingly increased. In any event, however, the results as to volume and selectivity appear to be superior than those which are obtainable in the ordinary inductive coupling.

90 Figure 5 shows a convenient means of applying the capacitative strips of a coil. Solenoid coils are chosen for the illustration. The coils 45 and 17 are wound respectively on tubular forms 54 and 55. A strip of metal such as tin-foil, or any other conductive 95 metal, is fixed at 50 and 51 in the interior of the respective forms 54 and 55, the capacity strips being connected by conductor 52 as heretofore explained. It will be noted that the two strips of foil extend the full length 100 of the coils with which they are associated and as a result, are in capacitative relation with every turn. Thus the two coils 45 and 17 are connected by a compound capacity involving, first, the capacity of the several 110 turns of coil 45 with conductive strip 50, and, secondly, the capacity of strip 51 with the turns of coil 17. Such an arrangement will give excellent results in a radio receiver and 115 the relative selectivity may be controlled as desired by increasing or decreasing the width of one or both of the strips 50 and 51.

120 Figure 3 shows a construction embodying the same sort of capacity coupling which is employed in Figures 1 and 2. The Figure 3 construction differs from that shown in Figure 2 primarily in the use of a primary 56 for energizing coil 45. The primary winding is directly connected between the antenna and ground and eliminates the necessity for using any connection, direct or capacitative, between the antenna and the tuned coil 45.

125 Figure 4 shows an alternative coupling in the nature of untuned radio frequency trans- 130

formers which may be employed, if desired, between triodes 15 and 25, or any other thermionic valves in an amplifying circuit. A primary 31 receives the output from plate 30 of triode 15 and may be coupled to a source of plate current supply in the ordinary way. The grid coil 32' is similar to grid coil 32 with the exception that it is untuned. The two coils 31 and 32' are in non-inductive relation and are coupled capacitatively by means of the two capacitances 150 and 151 and the intervening conductor 520.

It will be apparent from the foregoing description that the invention is applicable to 15 tuned and to untuned circuits and may be developed in a plurality of mechanical forms, any of which is adequate to carry out the purposes of the invention. I prefer, however, in coupling an aerial circuit to a radio 20 amplifier, to employ two tuned circuits for connection by the capacitances herein described.

I claim:

1. An electrical circuit comprising the 25 combination of a plurality of successive tuned circuits substantially in mutual non-inductive relation, and a coupling between said circuits consisting of a plurality of capacitances in series each capacitatively related 30 to a tuned circuit.

2. An electrical circuit comprising the combination of a plurality of successive tuned 35 circuits substantially in mutual non-inductive relation, and a coupling between said circuits consisting of a conductor capacitatively coupled to a plurality of turns of each of said inductances.

3. In a radio receiver, the combination with 40 an antenna circuit and a grid circuit each including an inductance having a number of turns, of a metallic strip in capacitative relation to a plurality of the turns of each of said inductances, and conductive means connecting said strips.

45 4. In a radio receiver, the combination with an antenna circuit and a grid circuit each including an inductance having a number of turns, of a metallic strip in capacitative relation 50 to a plurality of the turns of each of said inductances, and conductive means connecting said strips, the width of such strips being such as to produce a desired degree of selectivity in the coupling between said inductances.

55 5. In a radio receiver, the combination of a plurality of successive circuits each including an inductance shunted by a variable condenser, of means coupling said circuits and including capacitances each capacitatively 60 related to an inductance and conductively connected.

65 6. In a radio receiver, the combination of a plurality of successive circuits each including an inductance shunted by a variable condenser, of means coupling said circuits and

including capacitances related to each circuit and conductively connected, each of said capacitances comprising a metallic strip capacitative related to a plurality of turns of the inductance in the circuit with which it is associated. 70

7. An electrical circuit comprising the combination of a plurality of coils and capacity strips in mutually conductive relation each extending across a plurality of turns of one 75 of said coils.
